UNITED STATES PATENT OFFICE

2,153,442

METHOD FOR CONDITIONING TOBACCO

Rush D. Touton, Cynwyd, Pa., assignor to Wurton
Machine Company, Philadelphia, Pa., a corpo-
ration of Pennsylvania

Application December 6, 1935, Serial No. 53,137

2 Claims. (Cl. 131—55)

This invention relates to a method for conditioning tobacco.

More particularly, in accordance with this invention a method is provided whereby tobacco will be conditioned for any desired purpose. Thus, for example, tobacco may be conditioned by moistening to adjust its moisture for fermentation, by moistening to prepare it for sorting, packing, for use in the manufacture of cigars, or other use. In particular, the method in accordance with this invention will be found highly economical and efficient for the preparation of tobacco for fermentation.

The method in accordance with this invention will, from the broad standpoint, involve subjecting tobacco in bunches or hands to a gas, as air, conditioned with respect to the nature of the treatment of the tobacco, as moistening. The gas, as air, will be generally circulated with respect to the tobacco and/or forcefully directed into the hands or bunches for the purpose of opening or spreading the leaves, and, at the same time, the hands or bunches will be subjected to movement through a circuitous path.

The method in accordance with this invention will involve increasing the rate of movement of the hands or bunches after the tobacco leaves have absorbed sufficient moisture to render them pliable.

From the broad standpoint the apparatus for carrying out this invention will comprise a chamber in which travels a conveyor arranged with substantially vertical reaches and adapted to support bunches or hands of tobacco. Within the chamber will be arranged a system of ducts provided with outlets arranged with respect to the conveyor for the delivery to the chamber of conditioned gas in a manner to promote general circulation with respect to the tobacco and for the direction of conditioned gas into the bunches or hands. Means for the conditioning of gas, as air, with respect to temperature and humidity or moisture content will be provided and will be so arranged as to effect recirculation of air from the chamber through the system of ducts.

The more specific details of the method and apparatus according to this invention will become apparent from the following detailed description of preferred embodiments of the apparatus and its mode of operation in carrying out the method with reference to the accompanying drawings in which:

Figure 1 is a side view, partly in section, of a form of apparatus employing this invention.

Figure 2 is a cross-sectional view on line 2—2 of Figure 1.

Figure 3 is a detail sectional view showing a portion of the conveyor system.

Figure 4 is a detail view showing the means of attaching the cross bars of the conveyor to the same.

Figure 5 is a cross-sectional view taken on line 5—5 of Figure 4.

Figure 6 is a side view, partly in section, of another form of apparatus employing this invention.

Figure 7 is a sectional view on line 7—7 of Figure 6, and

Figure 8 is a detail view showing a portion of the conveyor system shown in Figure 7.

Referring to Figures 1 and 2, *a* indicates a chamber which may be of suitable dimensions, depending upon the amount of tobacco to be treated, and which is desirably insulated. Within the chamber *a* is positioned an endless conveyor *b* of any desired type, and which may comprise a pair of endless chains *c*, *c*, from which are supported at spaced intervals cross members or bars *d*, *d*. As shown in Figures 4 and 5, each of a plurality of spaced links in the endless chains *c*, *c* is provided with a pin *10*, which is journaled loosely in a socket *12* at each end of a cross bar *d* so as to permit free rotation of the cross bars *d* about the pins *10*.

The chains *c*, *c* pass over a series of relatively large sprockets *e*, *e* secured to shafts *f*, *f* journaled in a frame *g* and positioned in line in the upper portion of the chamber *a*; and also over a series of relatively small sprockets *h*, *h* secured to shafts *f'*, *f'* journaled in the frame *g* and positioned in line in the lower portion of the chamber and in staggered relation with the sprockets *e*, *e*; and finally over sprockets *k*, *k* and *k'*, *k'*, all secured to shafts journaled in the frame *g* and positioned below and beyond the ends of the series of sprockets *h*, *h*.

The conveyor will be driven through a sprocket *24* on one of the shafts *f'* by any suitable connection with any suitable prime mover, as through a chain or belt *10* from an electric motor *80*, through the medium of a speed regulator *90* enabling the conveyor to be driven at various different rates of speed.

By virtue of the arrangement of the several sprockets, *e*, *h*, *k* and *k'*, the conveyor will have a number of pairs of substantially vertical reaches *l* in its travel from one end to the other in the series of sprockets *e* and *h*, which in pairs will be relatively close together, the pairs being relatively

30

35

40

45

50

55

widely separated; short horizontal reaches 20 and 22 and a horizontal return reach o supported by the brackets 14.

Within the chamber a adjacent one end thereof 5 is positioned a gas or air conditioning apparatus comprising a casing n provided with inlet opening 41 and containing a fan 40 positioned adjacent the inlet openings and driven by any suitable means, as, for example, a motor positioned 10 outside of the chamber. The fan will be arranged to deliver gas or air, drawn from the chamber, through humidifying, heating and/or cooling elements as a water spray 50 and a coil 60, through which may be passed steam or a refrigerant as 15 it may be desired for heating or cooling into a main duct s which extends longitudinally in the main part of the chamber along one side thereof.

The humidifier may, for various uses of the apparatus, as in the moistening of tobacco, operate in effect as a cooler, dehumidifier and humidifier and for such operation will be supplied with cold water at a temperature such as to effect desired cooling, dehumidification and humidification for the provision of gas or air having desired 25 wet and dry bulb temperatures for delivery to the duct s. Cooling may be effected by admission of cold air to the humidifier, or by the provision of a cool surface within the chamber a. Humidification of the gas in chamber a may be accomplished 30 by means of sprays in the chamber which may displace the air conditioning apparatus or be used in cooperation therewith.

From the duct s, a series of short vertical ducts t, t lead downwardly at one side of the chamber 35 and terminate in outlet openings from which conditioned gas is discharged for the provision of general circulation of air in the chamber. The air issuing from ducts t, t will rotate in the chamber so that the tobacco on the conveyor will 40 be surrounded by a sheath of conditioned gas.

A series of horizontal ducts v, v extend from the main duct s transversely of the chamber beneath the sprockets e, e on lines between the 45 pairs of vertical reaches l. Upwardly extending nozzles y, y, spaced so as to be in alignment with hands of tobacco as spaced on the cross bars d, d of the conveyor, lead from the top of the ducts v, v and are adapted to direct forceful jets of conditioned gas into the hands of 50 tobacco carried by the conveyor as it passes over the sprockets e, e.

In the carrying out of the method in accordance with this invention with use of the apparatus described above, the fan in the humidifying apparatus will be started and air conditioned as required will be delivered into the main duct and discharged into the chamber through the various ducts described. The conveyor will then be put in motion in the direction of the arrows, and charged with hands of tobacco x by dividing the 55 hands and straddling them over the bars d, d. The cross bars d, d are tapered upwardly, and thus act to prevent the hands of tobacco from tending to slip off. If desired the hands may be 60 secured to the cross bars without straddling by means of any suitable clip engaged under the butts. The conveyor will be charged at the front end, the hands being placed upon the bars d, d as they progressively pass along the short 65 horizontal reach 20. This charging portion of the conveyor may, as shown in Figure 1, extend outside the chamber a. As the hands are placed in straddling position along the cross bars d, they will automatically assume a position with the 70 leaves pendant, and due to the free rotation of the 75

cross bars d about their connection with the chains c, c, the hands will retain this position with the leaves pendant throughout their entire passage through the chamber a on the conveyor b.

Thus, despite the many changes of direction in the path of the conveyor b as it passes over the sprockets e and f, the hands of tobacco on the cross bars d, will remain fixed in position with the leaves pendant, and will have no tendency to slip or fall off of the conveyor.

If the tobacco to be treated is in the dry state in which it is received by the fabricator of, for example, cigars and is to be conditioned for fabrication, the hands or bunches will remain on the conveyor, which will be driven slowly, for such considerable period as is necessary for the addition to the tobacco of sufficient moisture to bring it to the proper condition and consequently will make a number of complete circuits on the conveyor, including passage along the horizontal return reach thereof, or the conveyor being fully loaded with tobacco may remain still for a period and set into motion. On the other hand, if the tobacco is to be treated to condition it for fermentation, as for sorting or packing, by adjustment of its moisture content, by moistening, the amount of moisture necessary to be added to the tobacco will be relatively small and conditioning can be effected in one passage of the tobacco at 20 a slow conveyor speed through the vertical reaches of the conveyor. In such cases the hands may be placed on the conveyor at the front horizontal reach 20 and removed from the conveyor at the short horizontal reach 22 at the rear of the 30 conveyor.

As the hands move downwardly and upwardly in the vertical reaches, the tobacco in a quiescent state will be subjected to conditioned air in general rotary circulation in the chamber by virtue of the air delivered into the chamber from the ducts t, t. As the conveyor passes around the sprockets e, conditioned air in forceful jets from the nozzles y, y passes directly into the hands. The discharge ends of these nozzles will be adjacent to 45 the tips of the leaves of the hands as the hands pass the nozzles. Desirably, the nozzles will discharge within, for example, two to eighteen inches, preferably about nine inches, from the tips of the leaves. These jets of air from the nozzles y, y serve to penetrate and open the leaves of 50 the hands.

Referring now more particularly to the form of apparatus shown in Figures 6, 7 and 8, it will be seen that there is provided a chamber a' similar to the chamber a described above and provided with an endless conveyor b' of any desired type which, in the specific form shown, comprises a pair of endless chains c' from which are fixedly supported at spaced intervals cross members or 60 bars d', d'. Each cross bar d' is provided with a plurality of suitable clips 33 adapted to grasp and firmly hold the butts of the hands of tobacco x.

The chains c', c' pass over a series of relatively 65 large sprockets e' secured to shafts journaled in a frame g' and positioned in line in the lower portion of the chamber a'; and also over a series of relatively small sprockets h', h' likewise secured to shafts journaled in the frame g' and 70 positioned in line in the upper portion of the chamber and in staggered relation to the sprockets e'. The conveyor chains, as they leave the last of the series of sprockets e', pass over sprockets 21 and under sprockets 29, thus forming the short 75

horizontal reach 35, and then over the sprockets 31 in a horizontal return reach α' back to the series of sprockets e' , h' .

The conveyor may be driven from any one of 5 the shafts of the sprockets e' by any suitable connection therefrom to a suitable prime mover as through a chain or belt from an electric motor desirably placed outside the chamber a' .

By virtue of the arrangement of the several 10 sprockets the conveyor will have a number of pairs of substantially vertical reaches γ' in its travel from one end to the other in the series of sprockets e' and h' which, in pairs, will be relatively close together, the pairs being relatively 15 widely spaced.

Within the chamber a' , adjacent one end thereof, is positioned a gas or air-conditioning apparatus, similar to that described above in connection with Figures 1 to 5, comprising a casing 20 n' from which a main duct s' extends longitudinally in the upper part of the chamber along one side thereof. From this main duct s' a plurality of branch ducts t' extend downwardly along one side of the chamber and across the 25 bottom of the chamber beneath the conveyor, terminating in the outlets 25. From these outlets 25 conditioned gas is discharged for the provision of general rotary circulation of air in the chamber.

30 In carrying out the method in accordance with this invention with use of the apparatus described above, the humidifying apparatus will be set in operation for the circulation of conditioned air within the chamber a' . The conveyor will then 35 be set in motion in the direction of the arrows and charged with hands of tobacco x by fastening the butts of the hands in the clips 33 on the cross bars d' . The conveyor will be desirably charged as the cross bars d' pass through the 40 short horizontal reach 35. The hands of tobacco x on the conveyor will then pass over the sprockets 31 along the horizontal reach α' and downwardly and about the sprocket e' . The several 45 changes of direction which will occur in the passage of the hands of tobacco along the conveyor in this manner will serve to agitate the hands to insure a more even take up of moisture from the conditioned atmosphere and will also 50 act to separate the leaves of the hands as they become progressively moistened. As the hands of tobacco pass up the vertical reaches γ' and over the relatively small sprockets h' , it will be seen that they are rapidly inverted through an angle substantially greater than 180° in their 55 passage about the sprockets h' , as is best shown in Figure 8. This is due to the fact that the hands of tobacco, because of their position on the conveyor, pass around the outside of the small sprockets h' , which results in inversion of the 60 hands through 180° , the inversion occurring at an increasing rate, at first slowly and finally into relatively increased rapidity. This inversion serves to thoroughly agitate and open up the 65 hands of tobacco as they become progressively moistened and to insure that each leaf in the hand is thoroughly and uniformly moistened.

As has been indicated, if the tobacco to be conditioned by moistening requires the addition of only a relatively small amount of moisture and the bunches are loose and open when applied to

the conveyor, the conveyor can be operated at a speed with respect to the combined length of the vertical reaches such that the desired conditioning can be effected in one passage of the vertical reaches, since due to the manipulation of the leaves by the forceful air jets and the penetration thereof into the hands, or by the quick and rapid inversion of the hands, the conditioning will proceed relatively rapidly and with uniformity. 5

As will be appreciated, the conditioned air discharged through the duct system for general circulation and manipulation and penetration of the bunches or hands is recirculated with adjustment of its condition by passage through the 10 humidifying apparatus, which, dependent upon the nature of the treatment to be given to the tobacco, will act to cool or heat, humidify or dehumidify the air to the temperature and relative 15 humidity suitable to the particular treatment. 20

As will be appreciated, numerous and various modifications in detail may be made in the apparatus and in the modus operandi above described without departing from the scope of this 25 invention.

As will be appreciated, the conditioning of the gas for delivery to chamber a or a' may be automatically controlled by any suitable device responsive to the condition of the gas in the chamber and capable of manipulating the various heating, cooling and humidifying devices. 30

In proceeding for the carrying out of the method of this invention, it will frequently be desirable to operate the conveyor at varying speed, dependent upon the degree of moistening of the 35 tobacco. Then, when tobacco is dry, a relatively slow speed of the conveyor will be advantageous. As the tobacco absorbs a certain amount of moisture, the speed of the conveyor will be increased. The tobacco, after absorbing sufficient moisture 40 to have acquired a relative pliability, will benefit in the absorption of further moisture by the incessant manipulation attainable by increased conveyor speed and resulting in more complete opening of the hands in this conditioned atmosphere. As will be appreciated, the condition of the atmosphere in chamber a is maintained at 45 substantially a uniform relative humidity.

What I claim and desire to protect by Letters Patent is:

1. The method of conditioning tobacco which includes moving dry tobacco in a conditioned atmosphere for the purpose of moistening the tobacco characterized by the fact that the rate of movement of the tobacco in the conditioned atmosphere is increased after the tobacco has absorbed sufficient moisture to have acquired a pliability. 50

2. The method of conditioning tobacco which includes moving dry hands of tobacco in a conditioned atmosphere in an enclosed area for the purpose of adding a given amount of moisture to said hands, characterized by the fact that the rate of movement of the tobacco in the conditioned atmosphere is increased after the tobacco has absorbed sufficient moisture to have acquired pliability, and that after the rate of movement of the tobacco is increased the tobacco is subjected to the action of jets of conditioned air. 65

RUSH D. TOUTON. 70
